UNITED STATES PATENT OFFICE

LENNIE WELLS, OF LONG BEACH, CALIFORNIA

UNDERREAMER

Application filed May 12, 1928. Serial No. 277,182.

My invention relates to rotary well drilling tools, and more particularly to under reamers to which may be attached a tool of some sort, said under reamers being adapted to be attached to a rotary member, such as a string of drill pipe and be rotated therewith.

It accordingly is an object of my invention to provide a novel form of well drilling tool having a set of rotary cutters adapted to be expanded outwardly from or retracted within a body or casing, means being provided within said body or casing for expanding said cutters outwardly.

Another object of my invention is to provide a novel form of indicating means for indicating that the cutters are expanded or retracted, means being also provided for operating said indicating means.

The above and further objects and advantages of my invention, as will hereinafter more fully appear, I attain by the mechanism described in the specification, and illustrated on the drawings, forming a part of my application.

Reference is had to the accompanying drawings, in which similar reference characters denote similar parts. In the drawings, Fig. 1 is a vertical sectional view of my invention, showing the cutters in retracted position.

Fig. 2 is a transverse cross-sectional view, taken on the line 2—2, Fig. 1, looking in the direction of the arrows.

Fig. 3 is a similar view taken on the line 3—3, Fig. 1.

Fig. 4 is a part sectional and part elevational view of the invention, showing the cutters in fully expanded position.

Fig. 5 is a transverse cross-sectional view, taken on the line 5—5, Fig. 4, looking in the direction of the arrows.

Fig. 6 is a similar view, taken on the line 6—6, Fig. 4.

Fig. 7 is a similar view taken on the line 7—7, Fig. 4, and

Fig. 8 is a fragmentary vertical sectional view showing a modified form of indicating means.

Describing my invention more in detail,

I provide a body or casing 2, provided with a hollow portion 4 adapted to house a mandrel 6, preferably detachably associated therewith, the casing or body 2 being provided with a preferably tapered extension 8, screw-threaded as at 10 so as to associate the same with a rotary member, such as the string pipe of a well drilling equipment, the lower portion of said body, if desired, being provided with a socket or other member 12, screw-threaded as at 14, to receive a drilling or other tool.

The body 2 is provided with a cooling medium passage 16 aligning with a similar passage 18 in the mandrel 6, the lower or outlet portion of the passage being opened and closed by a valve 20, the function of which will presently be described.

Mounted within the body 2 is a set of carriages, designated generally by the numeral 22, which carriages are preferably removable from said body, and are unconnected to any part of the structure of the device. These carriages have both a radial and axial movement with respect to the body 2 or the mandrel 6, their movement being guided by complementary devices, 24 and 26, respectively on said carriages and on said mandrel, which devices are adapted to coact, as seen in Figs. 1 and 4, so the movement of said carriages will always be had in unison.

With each carriage 22 I associate in any manner preferred, a cutter 28, preferably of the rotary type, and vertically positioned on vertical shafts 30, associated in any preferred manner with the carriages 22.

If desired, an inclined cutter 32, also of the rotary type, and mounted upon an inclined shaft 34, may be provided on each of the carriages 22, and movable therewith, both sets of cutters being adapted for special use in connection with hard earth formations, said cutters functioning to chip away such formations; and when said tool is used in other formations, other cutters may be used.

For the purpose of limiting the downward movement of the carriages 22, I provide the mandrel 6 with a ledge or other member 36 for engagement with the ledges 38 of the carriages 22. (Fig. 4).

To move the carriages 22 outwardly, but not inwardly, I provide a suitable spring 40, which spring rests on the top of a valve casing 42 (Figs. 1, 4 and 6), presently to be described, and its top portion engages a suitable washer or other member 44, surrounding the mandrel 6. The spring 40 moves the washer 44 upwardly, which washer is in continual engagement with the lower portions 46 of each of the carriages 22, and hence moves said carriages outwardly and radially with respect to the body 2 or the mandrel 6, said carriages being guided in their movement by the complementary devices 24 and 26 respectively on the carriages 22 and the mandrel 6.

The inward movement of the carriages 22 (precisely as their outward movement) is accomplished by the engagement of the top portions 48, preferably rounded as seen in Figs. 1 and 4 for this purpose, with the pipe as it is withdrawn from the hole, the insertion with said hole being accomplished by holding said carriage inwardly against the pressure of the spring 40 by means of a binding wire, which is cut or removed after the tool has been inserted in the hole.

The valve casing 42 has a top portion 50, preferably screwed on to the lower portion of the mandrel 6, and as hereinbefore stated, the spring 40 rests thereon, said valve casing being held in position by a suitable screw plug 52, cut-away as at 54 to provide a ledge which has a preferably squared portion 56 cut therefrom (Fig. 7) for the engagement with a suitable tool or wrench to screw said plug in place to support the valve casing 42.

That the operator may continually be informed as to the exact position of the cutters 28, (out or in) an indicating means or valve 20, pivoted as at 60 to the top of said valve casing, and provided with an operating pawl or other member 62, is provided, said valve, when open, as in Fig. 4, indicating that the cutters 28 are in outward position, the pump being in operation when said valve is open, the circulating medium within the passages 16 and 18 freely flowing therethrough. When said valve is closed, as indicated in Fig. 1, the passages 16 and 18 are closed, stopping the pump.

It will be understood that the valve 20 is opened by the pressure of the circulating medium; to close said valve, the bolts 58, preferably screwed to the washer 44 are provided, which bolts are adapted to pass through perforations in the top 50 of the valve casing 42, one of said bolts functioning as a guiding means to prevent binding, and the other to operate the pawl 62 to close the valve 20, said bolts, of course, travelling with the washer 44, with or against the pressure of the spring 40, to expand the cutters outwardly, said cutters being retracted as hereinbefore explained.

In Fig. 8 I have shown a slightly modified form of indicating means in which the body 2' is provided with the plug 52' and wrench opening 56', the valve casing 42' resting thereon, and the valve 20', opening and closing the passage 18' of the mandrel 6', bolts 58' being provided as in the other form of my invention. In this case, however, a pawl 62' is operated by the right bolt 58', a spring S' tending to hold the valve 20' in closed position. The operation is identical with that previously described.

While I have thus described my invention with great particularity, it will be clear that the same may be modified throughout a wide range. I accordingly do not propose to be limited to the exact details of construction shown and described, but reserve the right in practice to make any and all modifications thereof that fall within the scope of the appended claims.

I claim as my invention:

1. In an underreamer, a body, a mandrel adapted to be inserted in said body through an opening in the lower portion thereof, means in the lower portion of said body for detachably securing said mandrel in said body, means in said opening for securing said last-mentioned means in position so said mandrel will remain stationary in said body, a set of cutters in said body and adapted to be moved relatively to said mandrel, and said body, and means associated with said mandrel for operating said cutters.

2. In an underreamer, a body, a mandrel insertable in said body through an opening in the lower portion thereof, an upper member surrounding said mandrel, a lower member adapted to be detachably associated with said mandrel, means associated with said mandrel and positioned between said members for holding said upper member in adjustable relation with said mandrel, means associated with both of said members whereby said members are adapted to move relatively to each other, a detachable support in the lower portion of said body, for supporting said lower member, and a set of cutters associated with said body and said mandrel, said cutters being adapted to be moved by said upper member.

3. In an underreamer, a body, a hollow mandrel in said body, a set of movable cutters adapted to be guided by said mandrel, means for projecting said cutters outwardly from said body, and a double acting valve for opening and closing the hollow portion of said mandrel, said valve, when closed, being adapted to cause the fluid pressure thus built up in said hollow portion to function as a positive signal to indicate that said cutters are not operating.

4. In an underreamer, a body, a mandrel in said body having a fluid passage therethrough, a valve cage associated with the

lower portion of said mandrel, a set of cutters in said body, means associated with said valve cage for projecting said cutters outwardly, and a valve in said cage for closing 5 said passage, said valve being adapted to indicate to the operator the operative condition of said cutters.

5. In an underreamer, a body, a mandrel in said body, said mandrel having a circulating medium passage therethrough, means positioned in the lower portion of said body for holding said mandrel in said body, a set of cutters in said body and adapted to be projected outwardly therefrom, means associated with said first mentioned means for projecting said cutters outwardly, a valve for controlling the lower end of said passage, and means associated with said first mentioned means for operating said valve.

20. 6. In an underreamer, a body, a mandrel in said body, said mandrel having a passage therethrough, a set of cutters in said body, means associated with said mandrel for projecting said cutters outwardly from said body, and for permitting said cutters to be moved inwardly with said body, a valve for controlling said passage, and means associated with said first mentioned means for operating said valve.

30. 7. In an underreamer, a body, a mandrel in said body, said mandrel having a passage therethrough, a set of cutters, associated with said mandrel and said body, means associated with said mandrel for projecting said cutters outwardly, and permitting said cutters to be moved inwardly in said body, a valve for controlling said passage and means associated with said first mentioned means for operating said valve and also for holding said 35 valve in closed position.

40. In testimony whereof I have signed my name to this specification.

LENNIE WELLS.
